UNITED STATES PATENT OFFICE.

HARVEY H. HOCKETT, OF DALLAS, OREGON.

WASHWATER RECEPTACLE.

Application filed December 23, 1922. Serial No. 608,688.

To all whom it may concern:

Be it known that I, HARVEY H. HOCKETT, a citizen of the United States, residing at Dallas, in the county of Polk and State of Oregon, have invented certain new and useful Improvements in Washwater Receptacles, of which the following is a specification, reference being had to the accompanying drawings.

10 This invention relates to improvements in the construction of sinks, wash basins and the like, and more particularly to a construction thereof providing in combination with a device of this character a conveniently arranged soap holder or tray.

An important object of this invention is to provide a device of this character forming a part of the normal construction of the wash water receptacle and which is arranged 20 so that the soap may be convenient of access and so arranged that it may at all times be readily removed.

A further object of the invention is to provide an addition of this character which 25 will not in any way detract from the appearance of the device with which it is employed and which will not interfere with normal use of the device.

I am aware that soap holders have been 30 combined in basin structures prior to this time but to my knowledge these soap holders have always been combined in the form of a depression formed in the upper surface of the basin upon which the soap is more 35 or less in the way and from which the same may be accidentally knocked into the water of the receptacle where it is wasted.

Other objects and advantages of the invention will become apparent throughout the 40 course of the following description.

In the accompanying drawings wherein for the purpose of illustration is shown a preferred embodiment of my invention and wherein like reference characters designate 45 like parts throughout:

Figure 1 is a sectional view showing a soap holder constructed in the wall of a bath tub;

Figure 2 is a transverse sectional view 50 through the soap holder;

Figure 3 is a sectional view showing a modified form of construction; and

Figure 4 shows the soap holder constructed in a splash board.

55 Referring now more particularly to the drawings, the numeral 10 indicates the wall

of a wash water receptacle, such as a sink, bath tub, wash basin or the like. By the term wall it will be understood that such devices as splash boards 10^a arranged above 60 the sink and not an integral part thereof are to be included. In the wall 10 in accordance with my invention an opening 11 is formed of sufficient size to permit of ready access of the hand while holding a cake of soap. Arranged at the rear or outer face of the wall 10 is a receptacle 12 consisting of a bottom 13, a rear wall 14 and an upper wall 15. This receptacle 12 is preferably cast integrally with the wall 10 and is merely in the 70 form of a recess or depression formed in the wall. The bottom wall 13 slopes rearwardly and downwardly toward the rear wall 14 and is provided upon its surface with ribs 16 in order that a cake of soap placed thereon 75 may not stick thereto.

This lower wall has formed at its rear or lower end an outlet 17 which is in communication with the outlet 18 of the wash water receptacle above the trap 19 associated therewith so that all water collected within the receptacle may be drained away without danger of any return gases from the soil pipe passing through such opening. In Figure 1, I have illustrated the connection between the outlets 17 and 18 in the form of a conduit 20 cored in the wall 10, but it will be readily understood that a conduit such as indicated at 20 may be provided having couplings 21 whereby it may be connected to the 90 outlets 17 and 18.

While I have stated that the receptacle 12 is preferably formed integrally with the wall 10 in casting the same, it will be readily understood that the receptacle may be attached 95 to the wall 10, as indicated in Figure 2, to cover the space behind the opening 11 which will be formed in this wall. With such a construction, the enamel coating 22 applied to the wash water receptacle and to the receptacle 12 will cover the joint therebetween completely hiding the same. With such a construction a coupled conduit will, of course, be provided. The location of the receptacle 12 upon a wash water receptacle is 100 a matter of choice. In the construction of wash basins, bath tubs and the like, this receptacle may be used in lieu of the ordinary overflow, in which use the conduit 20 will serve to return the overflow water to the 110 waste pipe above the trap 19 and below a plug 23 inserted to close the opening.

Many changes being possible in the positioning and construction of the soap receptacle in combination with the wash water receptacle, I do not limit myself to those specific structures hereinbefore set forth except as hereinafter claimed. In the appended claim it will be understood that the term "wash water receptacle" includes not only the receptacle proper but any of those vertical or substantially vertical splash boards such as are commonly provided with sinks. It will furthermore be understood that the term "integrally attached" includes that construction illustrated in Figure 2 wherein the receptacle 15 is made to all appearances a unitary portion of the wall 10 by the application of enamel thereto.

I claim:—

The combination with a wash water receptacle having an opening formed through the

side wall thereof below the upper edge thereof and permitting passage of the hand while holding a cake of soap, the usual drain outlet, drain pipe communicating with the drain outlet and plug for the drain outlet, of a receptacle arranged upon the outer wall of the wash water receptacle closing said opening and combining therewith to form a soap receiving pocket, the lower wall of said pocket being inclined and provided at its lowermost point with a drain opening, said drain opening being in communication with said waste pipe at a point intermediate the trap and the lower face of the plug when in position in the drain outlet whereby to provide a soap receptacle, and an overflow outlet for the wash water receptacle.

In testimony whereof I hereunto affix my signature.

HARVEY H. HOCKETT.
